ELECTRIC DISCHARGE LAMP

Leonard John Davies, Rugby, England, assignor
to General Electric Company, a corporation of
New York

Application December 7, 1935, Serial No. 53,320
In Great Britain December 12, 1934

1 Claim. (Cl. 176—122)

This invention relates to electric discharge lamps of the kind in which the discharge is adapted to start as a glow discharge and subsequently to develop into an arc discharge having a restricted luminous column of high intrinsic brilliancy, the atmosphere within the device being provided to this end.

In lamps of this type, as the light source consists of a column of highly ionized gas at high temperature, which is carrying a current of electricity, its position can be determined by forces such as those arising from convection currents and magnetic fields. I propose to utilize this fact to produce a lamp having novel and useful characteristics.

Lamps as at present manufactured suffer from certain disadvantages, amongst which may be mentioned the necessity for a choke or inductance or resistance in series with the lamp in order to stabilize it, owing to the arc-like or negative resistance characteristic of all known discharge lamps. A further disadvantage is that lamps of this type require, in general, a starting voltage higher than their actual operating voltage.

A lamp of the kind above set forth, according to the present invention has a low work function cathode and an anode (or two cathodes when used on alternating current), arranged in proximity to one another so as to allow the initiation of a discharge at a low voltage in an atmosphere of gas and metal vapour contained within the device, and means for creating a magnetic field located so as to deflect and lengthen the arc formed during operation. The winding producing the magnetic field may be in series with the lamp or may form part of the lamp circuit with other components. The lengthening of the arc path so produced will have the effect of increasing the voltage drop across the arc, and in suitable circuits, thereby increasing the power consumed under luminous output. I further arrange the magnetic field in such a way and in such form that the ordinary negative characteristic of the arc acts in such a way that the increased current that the arc takes has the effect of increasing the length of the arc and thus increasing its voltage drop. In this manner the arc is stabilized with a much smaller value of inductance than is normally required.

The accompanying drawing illustrates the invention.

In Fig. 1, which shows a somewhat diagrammatical form of lamp for operating on alternating current, 1 and 2 are a pair of self-heating cathodes each consisting of a heavy filament coated with a good electron-emissive substance surrounded by an open cylindrical metal shell 3, which cathodes are arranged closely adjacent one another and supported upon leads 4 sealed into

the lower end of a translucent envelope 6 which is of a glass capable of resisting attack by the metal vapour which is evolved during the operation of the lamp.

Connected in series with the cathodes 1 and 2 is an inductance 7 capable of producing during operation a magnetic field which deflects the arc upwards and lengthens it into the form somewhat as shown at 8, the bulb being designed to accommodate the extended arc. If, during operation, the arc tends to contract the voltage drop across it diminishes, resulting in increased current flow through the inductance 7 and an increase in the magnetic field strength. This tends to lengthen the arc. By this means it will be appreciated that a self-stabilizing operation is obtained.

In an alternative form of lamp shown in Fig. 2, the two cathodes 1 and 2, situated with only a small gap between them which may be in the neighbourhood of one inch are arranged at the top of the pear-shaped envelope 6. The envelope 6 is enclosed in an outer heat conserving translucent jacket 9, the space between which and the envelope 6 is preferably evacuated or may be filled with oxygen. The inductance 7 is located in a cap 10 cemented to the top of the outer heat conserving jacket 9. Convection currents tend to cause the arc to lengthen its path by attempting to extend upwards. In some cases this may tend to break the arc. This tendency is opposed by the magnetic field due to induction 7 so arranged that it tends to force the arc downwards and the strength of the field is so arranged that the arc takes the form of a U. The magnetic field may be connected in series or otherwise with the arc so that the arc and field tend to become self-stabilizing, in that any increase of current in the arc tends to lengthen the arc and increase its voltage drop, thus resisting the tendency for the current to increase.

What I claim as new and desire to secure by Letters Patent in the United States is:—

An electric gaseous discharge device comprising a sealed envelope containing a gaseous atmosphere, a pair of closely spaced electrodes within said device, said envelope having a spherical portion extending away from said electrodes in one direction, at least one of said electrodes being a thermionic cathode, and a magnet connected in series with the discharge within said device, said magnet being so disposed with respect to said electrodes that the magnetic field produced thereby reacts with a discharge between said electrodes to force it into a loop within the spherical portion of said envelope whereby the length and shape of said discharge is a function of the current flowing therethrough.

LEONARD JOHN DAVIES.
